UNITED STATES PATENT OFFICE.

HENRY L. BROWN, OF PATERSON, NEW JERSEY, ASSIGNOR TO BROWN SPIN-WAIGHT COMPANY, OF NEW YORK, N. Y., A CORPORATION OF NEW YORK.

TEXTILE APPARATUS.

1,149,718.

Specification of Letters Patent. Patented Aug. 10, 1915.

Application filed March 14, 1910. Serial No. 549,101.

To all whom it may concern:

Be it known that I, HENRY L. BROWN, of Paterson, New Jersey, have invented certain Improvements in Textile Apparatus, of which the following description, in connection with the accompanying drawings, is a specification, like letters on the drawings designating like parts.

This invention relates to textile apparatus, and is of special utility when embodied in mechanism for driving a series of spindles or similar members by means of a member, such as a flexible band, having a portion arranged for right-line movement in the direction of its length, although my improvements may be utilized in any part of the field of textiles for which they are adapted by their nature, the term "spindle" being used as a brief generic designation.

The primary object of my invention is to provide apparatus for spinning yarn continuously, without breaking, and preferably at a constant, predetermined speed, thus to produce a thread of a uniform number of turns to the inch, and also of uniform size and smoothness, of high tensile strength, and free from slugs, bunches or knots; a further important object being to provide for the simultaneous production of any desired number of such threads of the same size and strength, so that the operation of the loom or sewing machine in which they are to be used will not be interrupted by the necessity for repairing hundreds of breaks in one or more weak threads running through the warp or spool, and creating imperfections therein. Such simultaneous production of a large number of uniform threads involves the positive actuation at high speeds of a multiplicity of spindles having whirls of relatively small diameter, arranged closely adjacent to each other in the spinning frame, and as at the present day no means for driving such spindles exists which combines the capacity of a flexible band to drive closely arranged small whirls at high speed, with the continuous and uniform actuation characteristic of positive gearing, an important object of my invention is to provide a flexible band with means to be engaged positively with a rotatable member of small di-

ameter to permit actuation of one by the other at high speed, and this novel technical effect I claim broadly.

The expression "band" as used herein, is intended to designate the article usually described by that term, comprising a substantially continuous, inarticulate member as distinguished from a chain or series of links coöperating pivotally at their jointed ends.

With few exceptions, the spindles in operation throughout the world, estimated at over one hundred million in number, are driven by friction bands, and are subject to the disadvantages of operation inherent in frictionally operated actuating mechanism, including the friction due to lateral drag of the hand upon the spindle, which should be confined as nearly as possible to one pound when the band is properly set, but frequently runs up to three and four pounds and sometimes to seven or eight pounds when the operative is careless, with an increment of from .00075 H. P. to .00170 H. P. per spindle for each pound of band tension added to the bands, at the ordinary speeds ranging from 4000 to 8000 turns a minute.

The tension on a band is apt to increase largely during periods of inoperation, when the bands are free to contract. At a very common tension of three pounds, to which the bands of an ordinarily well attended frame may pull at any time under heavy moisture conditions, estimating 80 spindles to the H. P., the band tension has been estimated to consume over forty per cent. of the total power required by the whole frame.

Accordingly it is an object of high importance in my invention to eliminate the tension factor wholly, and this I accomplish preferably by gearing my improved band tangent to the spindle whirl, gear or sprocket wheel, with little or no pressure thereagainst.

Frictionally driven bands and other frictional driving means are liable to slip on the spindle whirls, in which event the spindle runs slow; if the band leaves the whirl, and engages with the spindle blade or a spindle part of smaller diameter than the whirl, the spindle speeds up faster than its

neighbors. Other sources of variation in speed exist, all of which are obviated by my positively geared flexible band.

Among other important factors contributory to the attainment of the above object is the elimination from the spinning operation of environmental influences of a character tending to cause variations in the speed of the spindles, among which influences the irregular absorption of oil by the driving means is included and also the absorption of atmospheric moisture, which varies rapidly often from hour to hour and causes corresponding variations in the tension of the driving bands in common use to actuate the spindles, these bands being made ordinarily of yarn or other hydroscopic or absorbent materials. Similar tensional or other speed changes are also induced by the lint, dust and other extraneous substances with which the bands become loaded and their weight and diameter altered, such substances sometimes finding their way also between the whirl and spindle base, if the latter is not kept properly clean, the friction thus caused increasing appreciably the power required to run the spindle affected, thus reducing its speed, so that it will then turn out a thread weaker than those from other spindles running at correct speed.

Heretofore, the exposed driving bands have been known to take up dirt and sediment to an extent necessitating an extra consumption of .003 H. P. per spindle, which would amount to over half a horse power for a frame of average size, and the bands have also been known to absorb sufficient moisture from the atmosphere during a rainstorm to increase by 10 per cent. the power required to drive them.

In accordance with the preferred form of my invention, I have arranged for the complete elimination of many of the disturbing factors above recited, by the provision of a constant environment in which runs actuating band mechanism of any type suitable to drive the spindle device which may be selected for a given operation. A convenient mode of carrying into effect this departure from existing practice is to inclose the actuating band mechanism within a suitable container where it will be insulated from the atmospheric changes above recited, and also from the intrusion of foreign substances, and this insulation may be served further by placing in the container oil or other suitable fluid surrounding the actuating band mechanism wholly or in part.

In accordance with a valuable feature of my invention, furthermore I may, and I prefer to, form the driving band of non-hydroscopic material to avoid the absorption of oil, atmospheric moisture and the like, with its attendant evils, and for this purpose I prefer to form the band so,

whether or not the apparatus is provided with a positively geared band and with means to create an artificial environment.

In carrying my invention into effect to accomplish the above recited objects with maximum efficiency and notable simplicity, my positively operating driving means preferably takes the form of an endless flat ribbon of steel having apertures the walls of which constitute the driving surfaces, inasmuch as this type of band lends itself readily to submergence in the oil when I utilize oil in connection with the means to afford a constant environment, or to act as a lubricant for gearing, the flat ribbon creating least friction and being the most flexible of a given thickness, while the metal of the band serves as a convenient form of non-hydroscopic material for the composition of the actuating mechanism, in accordance with the preferred construction thereof as herein disclosed.

The various features of my invention will be illustrated and described fully in the accompanying drawings and specifications and pointed out in the claims.

In the drawings, Figure 1 is a view in side elevation of a spindle for spinning thread and the like, provided in accordance with my invention with a rotating member, in coöperation with which is shown a driving band, according to my invention; (this band is best seen in Fig. 8); the spindle being shown in Fig. 1 as mounted upon a special form of spinning-frame-rail, shown in vertical transverse section; Fig. 2 is a view in vertical section of the spindle and bolster illustrated in Fig. 1, on a somewhat larger scale; Figs. 3 and 4 show, in plan view and side elevation respectively enough of a spinning frame, of well-known form, and provided with a multiplicity of spindles having rotating members or "whirls" arranged in coöperative relation with a band, to illustrate the operation of the driving mechanism in this frame, in the construction of which my improvements have been embodied; Figs. 5, 6 and 7 illustrate respectively in plan, side elevation and perspective the whirl or rotating member separately, these figures showing a member having three projecting driving wedges, and Figs. 8, 9 and 10 are views in side elevation, plan and perspective of the same member, showing also a coöperating continuous band or endwise movable member in driving position; and Fig. 11 is a view similar to Fig. 2; of a modified form of spindle.

In the embodiment of my invention selected for illustration and description to enable a ready and complete understanding of my improvements, and referring first to Figs. 1, 3 and 4, I have there shown in vertical section, plan view and side elevation respectively, parts of a spinning frame of the type

used commonly in silk spinning, having a number of spindles, 60, which, in accordance with the preferred embodiment of my invention, are mounted on rails 63 within a container 69, and having whirls 1, driven positively, in accordance with my invention, by a band of suitable construction, one convenient form being illustrated in the band 13, which passes at each end around (see Fig. 3) pulleys, 74, 75, mounted respectively on shafts, 76, 77, the first-mentioned shaft being provided with a driving pulley 78 from which a belt 79 is shown as running with a quarter turn around direction pulley 80 to a suitable source of power not shown. The container 69 is formed in continuation of boxes 81 inclosing the pulleys 74, 75, so that all these operating parts may run in oil, the mechanism as a whole being supported in any suitable fashion, as by frame members 82. The part designated by the reference numeral 1 is a rotatable, spindle-actuating member, which may be of any convenient material, size and general contour, being shown in the instance illustrated as comprising a whirl, sleeve or hub, having peripheral actuating projections, 4, and a longitudinal bore 2 (see Figs. 5-10) adapted to receive and be seated upon a rotatable spindle part, such as the sleeve 3 of the spinning spindle 60 shown in Figs. 1 and 2.

The whirl 1, whatever its form, may be connected in any suitable manner with the spindle blade 60, to rotate the same, being mounted co-axially on the bolster and spindle preferably, however it may be connected with the blade, the expression "on the spindle" being intended to indicate this co-axial arrangement, as of a ring on a person's finger, and not to signify permanent fixation of the whirl to the spindle blade, which is not essential, although a convenient form of connection. The whirl or rotating member 1, may be conveniently formed of metal, and in the instance illustrated is shown as provided with three equidistant wedge-shaped projections, 4, whose apices 5 preferably lie in the same transverse plane, which may be termed the plane of operative movement, and in a peripheral circle, at the side of which the inclined surface 6 of the wedge (see Fig. 6) broadens gradually to the butt 7 of each wedge, which may be separated by a suitable space from the apex of the next wedge projection, the circumferential face 8 of the projections being preferably concentric and lying in the same cylindrical surface, while the apices and corners of the wedges respectively are preferably slightly rounded as indicated, so as to avoid sharp corners likely to catch and tear articles brought in accidental contact therewith, and also to avoid unnecessary friction upon the coöperating band. These projections may

vary in contour according to the requirements of the particular situation in which they are used, without departing from the spirit of my invention, and I have selected the double wedge form merely as one convenient embodiment, one of the valuable features of this form being found in the contour of the inclined edges 6 which preferably are not normal to the periphery of the sleeve throughout, but may be normal thereto for a short distance from the hub proper, as at 10, (see Fig. 5) and then the crown of the wedge or tooth preferably tapers outwardly at 6, decreasing in breadth toward its outer surface 8, the line 12 of demarcation between the normal portion of the wedge, and the tapered portion thereof, being shown clearly in Figs. 5 and 7.

In accordance with my invention, I provide a coöperating power-transmitting member 13 (see Figs. 8, 9 and 1) movable in the direction of its length, and preferably substantially continuous, and as a convenient embodiment of this member I have shown in the instance illustrated an endless band 90 of suitable material, such as steel preferably flexible enough to run readily upon the relatively small pulleys, 74, 75, and provided at intervals (preferably equi-distant) with openings 14 of any suitable size and shape 95 to receive successively the wedge projections 4 upon the rotating member and coöperate therewith to transmit power from the band to the spindles. The arrows in the respective figures indicate the direction of movement of the coöperating members in the instance selected for illustration.

Considering the band as the driving member, and referring particularly to Figs. 8 and 9, the operation of my improved driving band, constructed according to the novel principle already described, may be understood best perhaps by considering the walls of the apertures 14 to be divided into a plurality of driving regions *a*, *b*, *c* and *d*, (see Fig. 8) although as a matter of fact each wall is continuous and operates continuously upon the wedge projections 4, along the region of contact denoted by the line 12, (see Fig. 5) what is said about the upper wall *a*, *b*, *c*, and *d*, applying with equal truth to the lower walls *a'*, *b'*, *c'*, *d'*, when the wedge is symmetrical, having inclined surfaces on each side of the plane of rotation.

When the band is carried in the direction of the arrow Fig. 8, the walls of the aperture 14 grip the wedge member 4 with their portions *a*, *a'*, just as one would grip the wedge with the finger and thumb and pull it around in the direction of the arrow, and as it is thus pulled the wall portions *bb'*, take hold in turn and then the portions *cc'*, and *dd'*, the operation being continuous as already indicated, the contact being preferably in a series of infinitely small regions 130.

or points along the shoulder 12, this form of contact being desirable on account of the low friction factor, although I do not limit myself to the specific contour of the 5 wedges illustrated in the figures under consideration.

It will be noted, on close observation of Fig. 8, that the wall region a, a' is ready to grip the broad end of the rearward wedge 10 4, practically at the instant at which gripping engagement ceases between the gripping portion dd' , and the thin edge of the forward wedge 4, so that the rotative impulse imparted to the rotating member 1 is 15 substantially continuous, the degree of separation between the wedges respectively and between the coöperating apertures, as well as the contour of these respective parts, being regulated preferably to accomplish such 20 continuous, actuating engagement in most instances, although I do not limit myself to uninterrupted engagement.

As indicated in Figs. 8 and 9, the aperture 14 will preferably be slightly longer 25 than the base of the tooth, to afford slight clearance at each end, and thus permit the band to sit snugly in against the periphery of the hub 2 of the rotating member, and thereby gain the maximum rotative effect. 30 Summarizing then, this generic feature of particular importance, I have provided for driving spinning spindles positively, and have accomplished this, in the instance illustrated, by applying to the shank 60 of such 35 a silk spinning spindle as that shown in Figs. 1 and 2, a whirl 1, consisting of the rotating member already described, and having projections 4 with which coöperates the band 13 already described, whose apertures 40 receive the wedges 4 and their walls serve to drive the whirl and spindle when the band is moved in the direction of its length by suitable mechanism.

Certain novel features of this invention, 45 in its aspect of a power-transmitting apparatus, form the subject of generic claims in my application Serial No. 465,466, from which this present application has been divided, Letters Patent No. 957,650 having 50 been granted upon the same on May 10, 1910.

Many details of construction may be supplied as found requisite in particular installations. Suitable positioning devices, such 55 as idlers 11, may be provided at suitable distances. The reference numeral 61 indicates a spindle-supporting bolster which may be of any suitable construction, and is herein illustrated as of a well-known type 60 having a flange 62 to rest upon a rail 63, removably secured in place, as by bolts 63^x, and through the aperture 64 in which passes the threaded shank of the bolster, the latter being threaded to receive a retaining nut 66. 67 indicates a bobbin from which the

silk is run off in the instance illustrated. (See Fig. 4).

I prefer to support the rail 63, and the actuating mechanism removably on angle-pieces 68 extended along, and secured, as by 70 rivets, to the side walls of a container 69, of suitable shape, and preferably formed of metal, being provided with cover members 70, secured as by bolts 71, in order to provide for the use of oil surrounding the rotating parts, to lubricate the same continuously, the cover serving also to keep out dust and other extraneous substances, and to confine the steel band 13 against accidental displacement, with possible injury 80 to operatives, and I also prefer to have the bolster open at the bottom as indicated at 72 in Fig. 2, so that the oil in the container may have free access to the inner bearing 73 or step of the spindle. As the oil can 85 also work up under the whirl 1, the slip fit of the sleeve 3 on the bolster being shown with an exaggerated space in Fig. 2, to indicate such possibility, there will be to a certain extent a constant circulation of oil 90 along the bearing between the spindle and its bolster, and between the bolster and the sleeve, and much wear will be avoided thereby.

It is to be noted that the whirl 1 is preferably located at a region surrounding part of the bolster 61, which may thus afford an extended bearing for the interior of the whirl, the sleeve 3 serving as a wear member in the instance illustrated, as well as one 100 convenient means for connecting the whirl corotatively with the spindle-blade 60 (see Fig. 2).

In Fig. 11 I have shown a modified form of spindle especially adapted to linen and 105 cotton spinning, this modification comprising a sleeve 103 of suitable construction to the connected operatively with the spindle blade, as for example the well-known form of blade illustrated at 90; the sleeve preferably having a bobbin cup 109 formed integrally, or as a unitary structure, with the upper portion of the sleeve, while the lower portion thereof is shown as constructed to receive a whirl 101, having drive teeth 104 110 of the type already described with reference to the whirl 1, this being one suitable form of actuating means when the spindle is to be driven positively by a band such as that designated by the reference numeral 13 and 115 hereinbefore described. The sleeve 103 with its bobbin cup 109, and the whirl, 104, can be applied readily to existing spindles, to 120 equip them for actuation by my novel positive band-drive.

Having described and illustrated my invention thus fully and suitable means by which it may be put in practice, I wish it understood that I do not limit myself to the specific materials and construction selected 130

for illustration and description, nor in general otherwise than as set forth in the claims, read in connection with this specification.

5. What I claim and desire to secure by Letters Patent is:—

1. Apparatus of the class described, for treating thread and the like; said apparatus comprising a plurality of spindles provided respectively with peripheral V-shaped teeth; a support for said spindles; and an endless metallic band having V-shaped openings to receive said teeth; said band being constructed and arranged to engage progressively the successively presented portions of the inclined surface of each of said teeth to rotate said spindles positively; and means to actuate said band; substantially as described.

20 2. Apparatus of the class described, for treating thread and the like; said apparatus comprising a series of spindles in a row and provided respectively with peripheral teeth; a support for said spindles; a metallic band sustained to present a straight run substantially tangential to the toothed portions of said spindles, to engage said teeth positively, to rotate said spindles; and means to lubricate the coöperating toothed portions of said spindles and said band; substantially as described.

3. Apparatus of the class described, for treating thread and the like; said apparatus comprising a series of upright spindles in a row; a support therefor; and a metallic band constructed and arranged to operate said spindles positively; and means to surround said band and spindles at the region of operative engagement therebetween to contain lubricant in quantities sufficient to be engaged with said band, and thrown thereby, when in motion, to lubricate said region of operative engagements; substantially as described.

45 4. A spindle of the class described; comprising a blade having a bearing portion to enter a suitable support; such as a bolster; a sleeve connected co-rotatively with said blade; and having a portion to surround a part of said bearing when in operative position; and a sprocket-wheel-member com-

prising a hub mounted upon said bearing-surrounding-portion of said sleeve, and provided with a sprocket tooth of substantially V-shape in transverse section; substantially as described.

5. A support of the nature of a rail for apparatus to treat fibrous material such as thread; said support comprising an elongated trough-like member of sheet-metal; and an angle-piece secured to the inside of said member and constructed and arranged to receive and support said fiber-treating devices; substantially as described.

6. A support of the nature of a rail for devices, such as spindles, to treat fibrous materials; said support comprising an elongated, trough-like member of sheet-metal; angle-pieces secured to the respective sides of said member for a substantial portion of its length; a rail plate bridging the space between said angle-pieces and secured removably thereto; and cover members having cover portions to extend over the open top of said trough from the sides respectively, and having downward extensions; and cross-bolts passing through said downward extensions and the walls of said trough to hold said cover members in place.

7. Apparatus of the class described; said apparatus comprising a plurality of spindles provided respectively with actuating members having peripheral actuating projections with longitudinally inclined sides; a support for said spindles; an integral metallic band, substantially uniform in thickness throughout its extent, and arranged for right-line movement lengthwise past, and in tangent relation to, said actuating members, with apertures having longitudinally inclined drive walls, to engage said projections positively and progressively; and means to drive said band, to rotate said spindles positively.

Signed at New York in the county and State of New York this 12th day of March, 1910.
